UNITED STATES PATENT OFFICE.

ANDREW WESTLAKE, OF LEADVILLE, COLORADO.

CAR-TRUCK.

SPECIFICATION forming part of Letters Patent No. 292,454, dated January 22, 1884.

Application filed July 3, 1882. (No model.)

To all whom it may concern:

Be it known that I, ANDREW WESTLAKE, a citizen of the United States of America, residing at Leadville, in the county of Lake and 5 State of Colorado, have invented certain new and useful Improvements in Car-Trucks, of which the following is a specification, reference being had therein to the accompanying drawings.

10 My invention relates to a new construction of short car-trucks having independent axles; and it consists in a truck-frame having a double line of arch-bars on each side of the truck, rigidly connected by means of channel-plates 15 and bolts, and in other improvements, all of which will be fully understood by the following description and claims.

In the accompanying drawings, Figure 1 is a side view of my improved car-truck. Fig. 20 2 is a top view of the same. Fig. 3 is an end view. Fig. 4 is a bottom view. Figs. 5, 6, and 7 are detached and enlarged views.

My truck-frame is made with a double line of arch-bars on each side of the truck, one 25 line being placed each side of each wheel and each line having three arch-bars, or two arch-bars and a tie-bar, as shown at A B C, Fig. 1. These lines of arch-bars are connected by two channel-plates, D, and bolts E, as shown in 30 Figs. 1 and 2. They are also stiffened by means of the oil-boxes F, having flanges f on their inside ends, which are riveted or bolted together in the middle of the truck, thus stiffening the truck and serving the purpose of a 35 continuous axle to keep the wheels in gage. The outside ends of these oil-boxes are fastened to the inside line of arch-bars by pedestal-bolts Q. A series of diagonal braces, H, on the under side of the truck, are bolted to 40 the arch-bars. These braces extend from the inner line of arch-bars on one side of the truck to the inner and outer line of arch-bars on the other side of the truck, and are bolted to the same. A set of short cross-braces, M, connect the two inner lines of arch-bars and assist in stiffening the truck-frame. Between 45 the wheels are two long oil-boxes, F, having openings at the side instead of the end, said openings being provided with covers, Fig. 50 3, thus affording convenient access to the interior of the oil-chambers for the insertion of

brasses of the inside journals, and also for packing and oiling the same. The outer oil-boxes, N, are of the usual form. The back ends of the inner and outer oil-boxes are 55 chilled to prevent wearing away by the hub of the wheel, and thereby prevent the end-thrust of the axles. A chilled washer, K, is made open at its lower end, so as to be sprung over the axle between the hub of the wheel L 60 and the oil-box F, as seen in Figs. 5 and 6, for the purpose of preventing end-thrust of the axle as the hub of the wheel and the back end of the oil-boxes become worn. This chilled washer varies in thickness as the space to be 65 filled may require.

Between the two channel-plates D is a swinging bolster, N, having a suitable end-play, and supported by elliptic springs O, resting upon the sand-board P, Fig. 4.

70 Coiled or rubber springs may be used, if desired.

Having described my invention, what I claim is—

1. In a car-truck, the combination, with a 75 double line of arch-bars, A, on each side of the truck, of connecting arch and tie bars B C, transverse connecting channel-bars D, and the diagonal long and short braces H and M, arranged substantially as herein shown and 80 described.

2. In a car-truck, a series of independent axles, in combination with the oil-boxes having chilled ends, and chilled washers K, substantially as and for the purpose herein shown 85 and described.

3. In a car-truck, the long oil-boxes F F, having flanges f f bolted together to stiffen the truck, substantially as herein shown and described.

4. Oil-boxes F F, provided with flanges f f, riveted together, with back ends of said boxes chilled, and having side openings, i, and covers therefor, substantially as herein shown and described.

90 95 In testimony whereof I affix my signature in presence of two witnesses.

ANDREW WESTLAKE.
